UNITED STATES PATENT OFFICE.

SARAH EMORY GLEASON, OF TACOMA, WASHINGTON TERRITORY.

BABY-WALKER.

SPECIFICATION forming part of Letters Patent No. 354,895, dated December 28, 1886.

Application filed November 2, 1885. Serial No. 181,647. (No model.)

To all whom it may concern:

Be it known that I, SARAH EMORY GLEASON, a citizen of the United States, residing at Tacoma, Pierce county, Washington Territory, 5 have invented a new and useful Improvement in Baby-Walkers, of which the following is a specification.

The invention is illustrated in the accompanying drawings, in which Figure 1 is a 10 transverse section of my improved perambulator. Fig. 2 is a longitudinal section. Fig. 15 3 is a top plan view corresponding to Fig. 1, the device being in the form of a perambulator. Fig. 4 is a top plan view with the device extended.

Referring to the drawings, A designates the 20 ends, and A' A" the sides, of a two-part extensible frame supported on legs B, having ordinary casters, b, and rocker-seats. Side 25 boards, H, moving in guides in either or both parts of the main frame, allow the same to be extended into a couch, as shown in Figs. 2 and 4, or to be forced into an approximately square form, as seen in Figs. 1 and 3.

D designates a fixed panel, secured in each 30 of the end parts, and these parts D comprise in part the bottom of the couch or crib. To one of these panels D is hinged at c' a movable panel, C', and to the other is hinged at c a movable panel, C. When the frame is extended, the panels D, C, and C' comprise 35 the bottom of the crib, the several panels having proper supports, which may be of any desired and approved form, and are not illustrated.

Hinged at e to the movable panel C' are two arms, E, and to the free ends of each of these arms is secured a hook, i, which in one position of the device engages keepers I, secured in proper position upon the lower surface of 40 the movable panel C.

By elevating the movable panels C C', forcing the parts of the main frame together, and engaging the hooks i of the two arms E in the keepers I, the device is transformed into a 45 perambulator. (See Figs. 1 and 2.) Hooks k upon the arms E, when engaged with eyes k' upon the bottom surface of the panels C, allow the arms E to be folded and held up out of the way when the device is serving as a crib. 50

Rockers G may be attached at will to the seats b'.

The child, standing between the parts C, C', and E, is supported on four sides, and the spaces between C' and A or C and A may be 55 used for playthings. The panels are preferably cushioned.

What I claim as new is—

The extensible frame A A' A" B, having 60 fixed panels D, and movable panels C and C', hinged to said fixed panels, combined with the hinged arms E, and engaging means I i, as set forth.

SARAH EMORY GLEASON.
